UNITED STATES PATENT OFFICE

WILLIAM A. FRENCH, OF MINNEAPOLIS, MINNESOTA

DESIGN FOR A HUMIDIFIER CABINET

Application filed April 16, 1931. Serial No. 39,501. Term of patent 3½ years.

To all whom it may concern:

Be it known, that I, WILLIAM A. FRENCH, a citizen of the United States, residing at Minneapolis, in the county of Hennepin and State of Minnesota, have invented a new, original, and ornamental Design for Humidifier Cabinets, of which the following is a specification, reference being had to the accompanying drawings, forming part thereof.

Fig. 1 is a front view of a humidifier cabinet showing my new design. Fig. 2 is a side view.

I claim:

The ornamental design for a humidifier cabinet, as shown.

In testimony whereof I hereunto affix my signature.

WILLIAM A. FRENCH.
